UNITED STATES PATENT OFFICE

2,573,082

OIL CONTROL DEVICE FOR ROCKER ARMS

John R. Winter, Jr., Detroit, Mich., assignor, by
direct and mesne assignments, to John R.
Winter, Sr., Detroit, Mich.

Application February 24, 1949, Serial No. 78,217

8 Claims. (Cl. 74—519)

1

The present invention relates to rocker arm mechanisms such as are employed as a part of the valve actuating means of internal combustion engines of the overhead valve type. The invention is particularly concerned with the controlled delivery of lubricant to the tappet and push rod bearing ends of such rocker arms.

In overhead valve engines of the type wherein the cam shaft which actuates the valves is journaled in the engine block, the cam shaft acts upon push rods slideable in the block, which in turn actuate rocker arms mounted on the head, the rocker arms acting upon the valve stems to open the valves against the resistance of valve springs. The problems involved in the controlled supply of lubricant to the tappet ends of such rocker arms have been most troublesome because, while lubrication of the tappet bearings and valve stems is necessary, any over-lubrication results in wastage of oil and excessive oil consumption. For various reasons, some of which will be considered herein, such over-lubrication has been difficult to prevent. Succinctly stated, it is the primary object of this invention to provide simple, inexpensive and reliable means for preventing such over-lubrication, while insuring an adequate supply of lubricant to the ends of rocker arms and to the associated valve stems and push rods.

It is now most common to provide forced feed lubrication to the rocker arm bearings by way of an oil passage in the rocker shaft, interconnected passages being formed in the rocker arms for conducting the oil to the ends of the rocker arm. The difficulty involved in the delivery of a controlled quantity of lubricating oil to the tappet end of the rocker arm and the valve stem is aggravated by the fact that any excess oil which finds its way to this end of the arm tends to be sucked into the cylinder along the valve stem during the intake stroke of the piston, particularly after wear has occurred between the valve stems and their guide bearings.

The most successful method thus far devised for providing accurately metered lubrication of rocker arm tappet bearings, valve stems, and push rods has been to provide lubricant conducting means of very restricted capacity but which is open to atmosphere, extending along the top edges of the rocker arm. One such system is disclosed in my copending application Serial No. 560,532, filed October 27, 1944, now Patent Number 2,509,661. Another such system is disclosed in O'Harrow Patent No. 2,288,831. While such systems effect a great improvement and provide

2

efficient oil control under ideal conditions, the effectiveness of control is not always complete, particularly under high speed operation when the oil viscosity is low. Moreover, the effectiveness of such control diminishes as the engine becomes worn. Especially after wear has occurred between the rocker arm bearing and shaft, but sometimes even in new engines, high speed operation causes oil to be discharged in the form of a jet from the top oil ports of rocker arms of the indicated types. This is highly undesirable because, due to the rapid reciprocatory movement of the arm, some of the oil thrown in such jet discharge strikes the valve end of the rocker arm, or strikes and floods other parts of the rocker arms and is thereby thrown about inside the engine head cover. Excess oil is thereby delivered to the valve stems, whence it is drawn into the cylinder and burned, the oil consumption of the engine being thereby increased.

This undesirable jetting of oil is apparently due to a pumping action which creates instantaneous high pressures in the oiling system and which is the result of clearance between the rocker shaft and the rocker arm bearing. When the push rod descends, if undue clearance has developed between the rocker arm bearing and rock shaft, the push rod allows the rocker arm to drop on the shaft so that all such clearance is at the bottom, which is in the area of a part of the oil porting which connects the passages in the arm to the passage in the shaft. The tappet at the other end of the rocker arm is held up by the valve spring acting through the valve stem, and when the rocker arm drops to the extent permitted by the bearing clearance, an increased quantity of oil is forced into the clearance space by the forced feed oiling system. When the push rod thereafter ascends, its first act is to lift the rocker arm, rocking it slightly about the tappet end to take up such clearance. Since this movement is very rapid, some of the oil which has accumulated in the bottom of the rocker arm bearing is forced upwardly through the passages in the rocker arm and out through the top hole with increased pressure. Even though the oil is also ejected from the sides of the worn bearing, the pressure increase is such that jetting occurs from the top hole. The oil thereby sprayed upwardly is thrown about in the space within the engine head cover, some of it being, as previously stated, thrown in the direction of the valve stems so that an excessive quantity of oil is delivered to the valve stems with

consequent loss of the excess oil which is sucked into the combustion space.

With the foregoing difficulties in mind, the present invention aims to prevent the above described jet-like discharge of oil, even after wear has developed between the parts in the manner described, and to insure that proper metered quantities of oil will nevertheless be delivered to the tappet and push rod bearing ends of the rocker arm, and adequate lubrication maintained.

In my copending application Serial No. 582,039 filed March 10, 1945, now Patent Number 2,523,489, I have disclosed an improved rocker arm construction which is also capable of overcoming the aforementioned difficulties, but the arm therein shown which is arranged to prevent upward jet discharge is of a relatively costly one-piece construction, and would of course have to be installed as replacement equipment in order to correct the difficulty in existing engines.

Another object of the present invention, therefore, is to provide oil control means of the indicated character adapted for installation upon the rocker arms of engines in service without the necessity of changing the rocker arms or dismantling any of the other working parts of the engine.

Still another object is to provide such oil control means in the form of simple, inexpensive sheet metal clips, so constructed that they may be very easily and quickly installed upon the rocker arms of existing engines, merely by removing the engine head cover and sliding the clips into position.

Other objects and advantages of the invention will become apparent upon consideration of the present disclosure in its entirety.

In the drawing:

Figure 1 is a side elevational view of a rocker arm provided with oil control means constructed in accordance with the present invention;

Figure 2 is a top plan view thereof;

Figures 3 and 4 are cross-sectional views taken substantially on the lines 3-3 and 4-4, respectively, of Figure 1 and looking in the direction of the arrows;

Figure 5 is a perspective view of one of my improved oil control clips; and

Figure 6 is a sectional elevation taken substantially on the line 6-6 of Figure 2, and looking in the direction of the arrows.

Referring now to the drawing, reference character 10 designates generally the body portion of a rocker arm constructed in general accordance with the disclosure of my copending application Serial No. 560,532 above mentioned. It will be appreciated that the details of construction of the rocker arm itself may be varied widely without departing from the present invention, however. By way of example but not of limitation, it will be appreciated that the oil control means of the present invention is equally applicable to rocker arms such as are shown in patents, Nos. 2,288,831 and 2,176,083.

Rocker arms of the general class indicated are provided with a generally vertically extending oil delivery passage as 12 through which oil is discharged into the space directly above the rocker arm. I have determined that for best operation the oil should flow upwardly from the mouth of opening 12 without jetting therefrom. In the rocker arm construction shown, the arm itself is formed of a single piece of sheet metal folded to form two laminae secured together by suitable means such as by spot welding, as indicated at

14. Along their upper edges, the two laminae, considered cross sectionally, are inclined downwardly toward their central plane of juncture to define a shallow trough-like channel 15 for conveying oil to the opposite ends of the arm. The slight inclination which defines this channel may be formed by the unavoidable drawing of the metal which occurs during the stamping of the arms, as disclosed in my copending application Serial No. 560,532,

In the area immediately adjacent the oil riser hole 12, a notchlike depression 30 is formed, which extends completely across both laminations of the arm, constituting in effect a transverse slot. Between this slot and the channeled portions 15 leading to opposite ends of the arm are upstanding ears as 31 which are bent outwardly away from one another to a slight angular divergence. A narrow V-shaped channel 33, 33' of restricted cross-sectional area is thereby formed connecting the transversely slotted area 30 with the oil-conducting channels 15. The ears 31 partially dam the oil, tending to prevent the flow of oil, except in limited quantities, toward the ends of the arm. It will be appreciated that by spreading the ears farther apart or moving them toward one another, the capacity of the channels between them may be varied, all as more fully explained in my previously filed applications above referred to. Only a limited quantity of oil is thus conveyed along the top of the arm to its ends. The excess oil is allowed to escape through the open sides of the slotted portion 31. Another method of controlling the quantity of oil delivered to the ends of the arm is by reducing the width of the top edge of the arm, as suggested, for example, in Patent No. 2,288,831. The point to be observed here, however, is that neither of these methods of controlling the quantity of oil which can flow along the top of the arm is successful in preventing over-oiling at the valve end due to the throwing of oil resulting from the jet-like discharge from the oil riser hole 12.

In accordance with the present invention, I provide a clip-like cover adapted to be secured to the arm in such manner that a baffling portion 20, shown as substantially flat, extends transversely across and spacedly above the upper end of the oil riser hole 12. The clip, which is integrally formed of sheet metal, is provided with four frictionally gripping leg portions as 16, adapted to embrace and bear inwardly against opposite sides of the arm to hold the clip in position.

The top baffling portion of the clip, which is generally rectangular when viewed in plan, prevents oil from squirting into the air above the arm. At both ends of the baffling portion are downwardly sloping control dam portions 22 formed as continuations of the portion 20, and inclined downwardly to such extent that at their extreme ends transverse edges 24 are formed which lie closely adjacent the upper edge of the arm and coact with the channel 15 to define a restricted orifice through which only a limited quantity of oil will pass.

It will be noted that the central baffle portion 20 is so positioned as to be substantially spaced above the mouth of the oil hole 12. With the rocker arm construction shown, such space is automatically provided by the transverse slot 30.

A pair of deflecting portions 25 extend angularly downwardly and outwardly from opposite sides of the baffling portion 20 and are substantially spaced from the sides of the arm, so that

5

substantial clearance is provided, affording side escape passages 26 of substantial cross-sectional area extending outwardly and downwardly from the space beneath the baffling portion 20, to permit free flow of excess oil to either side. Such laterally discharging passages 26 prevent the development of substantial pressures in the space above the arm and beneath the baffle section 20. By virtue of the provision of such vents of substantial size, the pressures in the aforementioned space 30 beneath the baffle cannot rise to a value which would cause the oil to squirt longitudinally along the top of the arm and beneath the end portions 24 of the clip.

It will be appreciated that the clip therefore not only prevents the discharge of the oil jet in a direction which would permit it to be thrown or sprayed upwardly, but quickly relieves the pressure in the space under the baffle portion 20 and above the oil hole, thereby preventing squirting of the oil toward the valve stem along the top of the arm.

The deflecting portions 25 may be of generally inverted channel form. Where the rocker arm is one having a transverse top slot such as the slot 30 in the illustrated rocker arm, the deflecting channel portions 25 are preferably slightly narrower than the slot, so that near their upper ends the downturned side webs 28 of the deflecting channels may project into the transverse slot 30 to serve as locating means, preventing longitudinal displacement of the clip along the top of the rocker arm. The lower edges of the channel side webs 28 also tend to prevent the deflecting portions from being bent downwardly, although the clips are preferably formed of spring steel and hardened, so that such distortion is not likely to occur.

It has been found that with the use of oil control clips constructed in accordance with the present invention, substantial savings can be effected in the oil consumption of engines of the indicated type, even though the valve actuating mechanism is badly worn.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. An oil control device for rocker arms of the type having an oil riser hole terminating at its upper end at an upper edge of the arm in a discharge orifice having an upwardly opening mouth, said device comprising a baffle portion, fastening means for securing said device upon an arm with the baffle portion extending transversely over and spacedly above said mouth in position to intercept oil discharged from the mouth in the form of a jet or surge, oil diverting portions carried by said baffle portion and directed laterally away from the sides thereof, spacing portions for maintaining a substantial clearance between said diverting portions and the lateral parts of an arm to which the device is attached, and supplemental baffling portions coating with the ends of said first mentioned baffle portion and extending transversely and downwardly therefrom, whereby said supplemental baffling portions may extend transversely with respect to such an arm and into close proximity to the top of the arm at two spaced positions between said mouth and the ends of the arm.

6

2. In combination with a rocker arm of the type having an oil riser hole terminating at its upper end at an upper edge of the arm in a discharge orifice with an upwardly opening mouth, an oil control device comprising a baffle portion, fastening means carried by said baffle portion and extending therefrom in a direction generally perpendicular to the plane of said baffle portion for securing said device upon an arm with the baffle portion extending transversely over and spacedly above said mouth in position to intercept oil discharged from the mouth in the form of a jet or surge, and a supplemental baffling portion coating with an end of said first mentioned baffle portion and extending transversely and downwardly therefrom in the same general direction as said first-mentioned baffle portion, whereby said supplemental baffling portion extends transversely with respect to the arm and into close proximity to the top of the arm in a position between said mouth and an end of the arm.

3. In combination with a rocker arm of the type having an oil riser hole terminating at its upper end at an upper edge of the arm in a discharge orifice with an upwardly opening mouth, an oil control device comprising a baffle portion, fastening means carried by said baffle portion and extending therefrom in a direction generally perpendicular to the plane of said baffle portion for securing said device upon an arm with the baffle portion extending transversely over and spacedly above said mouth in position to intercept oil discharged from the mouth in the form of a jet or surge, and a supplemental dam portion coating with an end of said first mentioned baffle portion and extending transversely and downwardly therefrom in the same general direction as said first-mentioned baffle portion, whereby said supplemental baffling portion extends transversely with respect to the top of the arm.

4. In combination with a rocker arm of the type having an upwardly opening oil discharge orifice, an oil control device comprising a baffle member, and holding portions carried by and extending from one side of said member and securing such member to the top of the rocker arm.

5. In combination with a rocker arm of the type having an upwardly opening oil discharge orifice, an oil control device comprising a combined dam and baffle member, and holding portions carried by and extending from one side of said member and securing such member to the top of the rocker arm.

6. In combination with a rocker arm of the type having an upwardly opening oil discharge orifice, an oil control device comprising a combined dam and baffle member including integrally formed angularly disposed sheet metal dam and baffle sections, and holding portions carried by and extending from one side of said member and securing such member to the rocker arm with both of said sections positioned transversely with respect to the arm.

7. An oil control device for rocker arms of the type having an upwardly opening oil discharge orifice, comprising a combined dam and baffle member including integrally formed angularly disposed sheet metal dam and baffle sections, and holding portions for securing such member to a rocker arm with both of said sections positioned transversely with respect to the arm, said holding portions including legs also formed integrally

with said member and extending from positions near the corners of said member.

8. A device as defined in claim 1 formed of an integral piece of sheet metal bent at its ends to define two such supplemental baffling portions and having downwardly bent inverted channels projecting from side edges between said ends and defining said diverting portions, each of the channels having depending side webs defining said spacing portions. 10
